FORK OR SIMILAR ARTICLE

Jose Barata y Barrera, Baltimore, Md., assignor to The Stieff Company, Baltimore, Md., a corporation of Maryland

Filed Mar. 14, 1966, Ser. No. 1,447

Term of patent 14 years

(Cl. D54—12)

FIG. 1 is a front elevational view of a fork showing my new design.

FIG. 2 is a side elevational view thereof.

FIG. 3 is a fragmentary front elevational view on an enlarged scale thereof.

FIG. 4 is a fragmentary rear elevational view thereof.

FIG. 5 is a fragmentary sectional view taken on the line 5—5 of FIG. 3.

FIG. 6 is a fragmentary sectional view taken on the line 6—6 of FIG. 3.

The essential features of the design reside in the full line portions of the drawing.

I claim:

The ornamental design for a fork or similar article, substantially as shown and described.
